Attorney

UNITED STATES PATENT OFFICE.

JASON McCARTY, OF WALLINS CREEK, KENTUCKY.

RAIL TIE.

Application filed September 21, 1925. Serial No. 57,651.

This invention relates to improvements in rail ties and is more particularly adapted to a device for supporting a pair of main rails and complementary switch points associated therewith, means being further provided for securing the rails on the ties. One of the important objects of the present invention is to provide means whereby a limited runway is formed for the switch point 10 on the ties.

Another important object of the invention is to provide a device of the above mentioned character which is particularly used in mines where a portable track and switch point are to be laid, my improved ties enabling the rails and switch mechanism to be readily and easily laid, base flange engaging clips being arranged on the ties for securing the rails and switch mechanism in proper 20 position on the ties.

A further object is to provide a device of the above mentioned character which is simple in construction, inexpensive, and furthermore adapted to the purposes for which 25 the same is designed.

Other objects and advantages of this invention will become apparent during the course of the following description:

In the accompanying drawing forming a 30 part of this specification and in which like numerals are employed to designate like parts throughout the same:

Figure 1 is a top plan view showing the manner in which a pair of main rails and a 35 pair of complementary switch points are supported on my improved ties, and

Figure 2 is a detailed perspective view of one of the clamping plates forming a part of the present invention.

In the drawing, wherein for the purpose 40 of illustration is shown a preferred embodiment of my invention, the numeral 1 designates an elongated metallic tie the same including the rail supporting surface 2 and the depending side flanges 3, the lower edges of which rest on the ground, and provide a means for supporting the ties. A pair of rails 4 and 5, respectively, of the ordinary construction, extend transversely across the 45 upper surface 2 of the tie 1 and the inner base flanges of the rails are cut away as at 6 so as to permit the complementary switch points 7 and 8 to be brought into cooperative 50 relation with the rails 4 and 5 when the switch point operating mechanism designated generally by the numeral 9 is actu-

ated. These switch points are pivotally supported at their rear ends to the forward ends of the rails 10 and 11, respectively, and as the construction of these rails is well-known in the art, a further detailed description thereof is not thought necessary.

A similar tie 12 is disposed below the rails at a point adjacent the pivotal connection between the switch points 7 and 8 and the 65 rails 10 and 11, respectively, as is clearly illustrated in Figure 1.

For the purpose of securing the rails in their proper positions on the ties are provided suitable clamping means the construction of which will be presently apparent. A pair of spring clips 13, each of which is formed of a single piece of spring metal, are pivotally supported intermediate the 70 ends thereof on the upper surface 2 of the 75 tie 1 at points adjacent the outer base flanges of the rails 4 and 5 as shown more clearly in Figure 1. The inner end of each of the spring clips is bent slightly upwardly. The intermediate portion of each clip is provided 80 with an opening through which the pivot 16 extends whereby each of the clips is pivotally supported on the tie 1 and it is obvious that when each of the clips is swung on its pivot in one direction, the inner upwardly 85 disposed end is swung over the outer base flanges of the respective rails 4 and 5.

For the purpose of securing the inner base flanges of these rails so that the rails will be rigidly supported on the tie 1, there is 90 secured on the tie 1 a substantially rectangular plate 19, the securing means therefor being shown at 20, suitable openings 21 being provided in each of the plates for receiving the fastening means. A lateral extension 22 is formed on the outer side edge of each of the plates adjacent the forward ends thereof and these extensions are also disposed slightly upwardly and adapted to extend over and engage the inner base 100 flanges of the rails 4 and 5 at a point adjacent the cut-out portions 6 of the rails so that a space will be provided between the rails 4 and 5 and the major portion of the outer side edges of the clamping plates 19 to 105 permit a sliding movement of the free ends of the switch points 7 and 8 on the upper surface 2 of the tie 1. The outer side edges of the clamping plates further limit the movement of the respective switch points.

The portions of the rails 4 and 10 and 5, respectively, which extend across the

upper surface of the tie 12, are secured thereon through the medium of spring clips 13, the inner ends of which engage the outer base flanges of the rails 4 and 5 in a manner similar to that in which the spring clips 13 engage the outer base flanges of the portions of the rails 4 and 5 which extend across the top surface of the tie 1. The outer base flanges of the rails 10 and 11 and the inner base flanges of the rails 4 and 5 are secured on the tie 12 through the medium of the spring clips 23 each of which is constructed of a single piece of spring metal the intermediate portion being provided with an opening for receiving the fastening element 25 and the respective ends of each of the strips comprising the spring clips 23 are bent upwardly. The outer ends of these spring clips engaging the inner base flanges of the rails 4 and 5 while the inner ends of the spring clips 13 engage the upper surfaces of the outer base flanges of the rails 10 and 11. This construction is more clearly illustrated in Figure 1. A pair of spring clips 25 similar to the spring clips 13 are arranged on the tie 12 and are adapted to engage the upper surfaces of the inner base flanges of the rails 10 and 11 so that the rails will be secured on the tie at 12 against lateral movement as well as vertical movement.

The simplicity with which the present invention is constructed enables the parts to be readily assembled or disassembled and a device of this character is more particularly adapted for use in mines where portable tracks are to be laid and with a tie structure of the character embodied in the present

invention as well as the rail clamping means associated with the tie, considerable time and labor will be saved in laying the rails. 40

Furthermore, the rail securing means as associated with the ties are so arranged as not to interfere with the operation of the switch points 7 and 8 and the actuating mechanism 9 provided therefor. 45

While I have shown the preferred embodiment of my invention, it is to be understood that various changes in the size, shape and arrangement of parts may be resorted to without departing from the spirit or sacrificing any of the advantages of the appended claim. 50

Having thus described my invention what I desire to claim and secure by Letters Patent is:— 55

In combination with a pair of main rails, and a pair of cooperating switch points associated with an additional pair of rails, and a rail supporting tie over the surface of which the free ends of the switch points 60 are disposed; of a pair of rectangular shaped plates secured on said tie at points adjacent the free ends of the respective switch points, the outer side edges of the plates being spaced from the inner sides of the respective switch points, a lateral extension formed on the side edge of each plate adjacent the forward end thereof and adapted for engagement with the respective inner base flanges of the first mentioned pair of rails, 65 the spaced plate providing a limited run way for the switch point. 70

In testimony whereof I affix my signature.
JASON McCARTY.
